UNITED STATES PATENT OFFICE.

CARL J. F. JOHNSON, OF CLEVELAND, OHIO.

FURNACE-DOOR.

967,927.

Specification of Letters Patent. Patented Aug. 23, 1910.

Application filed December 2, 1909. Serial No. 531,025.

To all whom it may concern:

Be it known that I, CARL J. F. JOHNSON, a citizen of the United States, residing at Cleveland, in the county of Cuyahoga and State of Ohio, have invented certain new and useful Improvements in Furnace-Doors, of which the following is a specification.

My invention relates to furnace doors, and the invention consists in an improvement upon a furnace door of which I am the inventor and for which Letters Patent of the United States were issued October 29, 1907, and numbered 869,575. In the said patent the style or type of furnaces in or with which my improved door is especially intended to be used is such, for example, as billet heating furnaces and re-heating furnaces of one form or another wherein blasts of gaseous fuel or other excessive heat producing agent is employed, and in consequence of which it is difficult to confine the gas in the furnace, especially in cases where there are a number of openings in the walls of the furnace through which stoking or the like may be accomplished. These extreme conditions of heat make it difficult to maintain effective closure of the furnace and are especially calculated to burn out metallic doors in the fronts of furnaces. It was my object, therefore, in my original application to meet these and kindred difficulties in furnaces of this general character and to render the doors heat proof, and while it appears that the principle upon which I was working was correct as a principle, the means employed have proven to be utterly defective and insufficient to accomplish the results sought, and hence I have made the improvement constituting the subject matter of this application and which has rendered the door eminently practical and successful. For example, the door as built in said Letters Patent was a cast metal structure and for the most part in one piece, and had a water chamber and an air chamber with draft passages therefrom into the furnace, while the water jacket was provided with both inlet and outlet passages or pipes at the top of the door. But practical tests demonstrated that this was an exceedingly faulty construction, because the water made simply a short circuit from the inlet to the outlet at the top of the door, while the water in the other portion of the door becoming intensely heated, formed steam and

thus created a back pressure against the water supply which really prevented the flow of water at all as I had planned. This of course would expose the door to the intense heat of the furnace without protection or relief, and with the uneven expansion and contraction that inevitably followed the door was quickly warped or cracked and rendered practically worthless. Hence my present improvement, which entirely overcomes these objections and provides a door wherein the water and air perform their functions in the most satisfactory manner, and a thoroughly effective construction of door is afforded.

In the accompanying drawings, Figure 1 is a front elevation of the door and attached parts, and Fig. 2 is an edge elevation thereof partially sectioned at the bottom. Fig. 3 is a plan or top view looking down upon Fig. 1. Fig. 4 is a view of the door looking from the inside with the inner plate removed and the connecting bolts and air tubes in cross section. Fig. 5 is a sectional elevation of the complete door taken on a line corresponding to 5—5, Fig. 4. Fig. 6 is an enlarged sectional view of one of the transverse air tubes and showing the manner of connecting same at its ends with other parts.

Having reference to my new and improved door in detail, it will be observed, first, that instead of being a unitary structure it is constituted of several distinct and different parts comprising a middle or interior part or portion B of cast metal and referred to hereinafter as the body. As such the said body is of the full size of the door as viewed in outline with a main portion 2 having sundry perforations or holes through the same for the tubes 3 and the bolts 4 as well as having a stoking or peep hole 5 and a rim 6 entirely about its edge and extending inward for the most part from the flat main portion 2. This body or frame is the only cast metal portion of the door and serves as a support for other parts including especially the inner preferably steel plate E and the outer face plate F, which conform to the outline of body frame B and are secured thereto as shown. That is the face plate F is fixed to said body by means of screws through its side edges, while rear or inner plate E, which has to sustain the exposure to the heat of the furnace, is secured to said body not only by

2 screws through its side edges in the edge of rim C but especially by means of bolts 4 adjusted and locked upon body B through the variously scattered holes over its middle, 5 especially. These bolts are threaded at both ends and one end is screwed into plate E and the other end passes through corresponding holes in the partition or main flat portion 2 of body B and is locked thereon 10 by a jamb nut 8 on one side and a fastening nut 9 on the other side. In practice the said bolts are first inserted in plate E and the nuts 8 are then adjusted thereon so as to be uniformly and evenly spaced from 15 said plate, and said bolts are then inserted in the holes in body B and fastened by nuts 9. The same practice is observed with tubes 3 as to both plates B and E, and lead gaskets 10 are interposed between the nuts 8 and 9 in connection with both tubes 3 and bolts 4 to prevent possible leakage at said points, and the peep or stoking hole has a wall the full depth of the rim or outer portion 6 of the body B and has inner plate E 20 also secured thereto by screws.

The rim 6 of the body B extends about half as far outward from the main or flat partition 2 of the body as it does to the rear thereof, and this construction provides an 30 air chamber in the front portion of the door and a water chamber or jacket in the rear portion thereof behind partition 2 with the air conducting tubes passing from the air chamber through the water chamber and 35 bodily exposed therein except at their ends. The said tubes are arranged about or near the outer edges of the door in such manner that they will discharge the air within the furnace next about the jamb of the door all 40 around and by driving back the gases therefrom, prevent possible burning out of the said jamb or wall of the furnace. As to this arrangement of said tubes it is to be especially observed that injection of air 45 therethrough carries initial combustion inward far enough to effect the ends desired through the medium of the inflowing air. Otherwise, or over the middle portion of the door there is no such danger and hence 50 solid bolts are found best for this portion of the door structure. Again, in stoking certain large furnaces the labor of several men frequently is required to handle a single stoking bar or poker. Hence I conceived 55 the idea of a roller K to rest the bar upon at the front and bottom of stoking hole 5 and whereby half the labor formerly required can do the same work with much more ease and facility.

60 Water and air supply may be wholly at the top of the furnace door by pipe connections N and M, or air pipe M at the top may be closed and the supply of air be by pipe P injected under suitable pressure into 65 mouth 16 in the side of the door, and the ex-

haust of water is by pipe O while the air goes to the furnace by ducts or tubes 3.

As to the water supply pipe N, said pipe is shown as extending down into the water chamber or space in the door near the bottom thereof, while the exhaust O is from the top of the door. Thus the water is caused to traverse the entire depth of the door to find the outlet and all portions thereof are uniformly cooled and there are no steam pockets or the like possible anywhere to make the cooling uneven or to defeat the freest possible circulation of the water. The door as a whole is designed to be bodily raised when opened and any suitable connections with the several pipes M, N, O and P may be made to permit such movement, whether the connection be by hose or sliding or joined pipes of any available or preferred construction. The hole or opening 5 in the door has the usual lid or cover 17 adapted to swing over the same from the side and above or over roller R.

In operation the door herein does not differ materially from that shown and described in my patent, and the invention I now claim lies particularly in the improved construction of the door whereby it is rendered practical and durable for service. In fact I find after protracted tests in which it has been subjected to the most trying conditions of heat and exposure that it remains cool and works perfectly and does not show the slightest tendency to buckle or become distorted or crack in any part. 90 The air is delivered to the door by pipe M or P is under more or less pressure as conditions may require, and a blower or other device to supply such pressure may be employed, the object being to produce or promote such flow of air through the tubes 3 as will effectually prevent accumulation of combustible gases about the edge of the door and the jamb and the consequent destruction of the brick work as above described. 95 The structure as a whole is knock-down or separable as occasion may demand, so that if for any reason any part or portion thereof shall require repair or replacement the same can be done without loss or destruction of the remaining parts. This is important, because if the door were a unitary or single piece structure as in my patent the impairment of a portion would necessitate the discarding of the entire door, 100 which was and is a very serious objection.

110 What I claim is:

1. A furnace door having a water chamber in its inner side and an air chamber in its outer side and constructed with a body providing a partition between said chambers, and separate inner and outer plates secured upon their edges to said body, and separate air conducting tubes fixed at their ends in 115 said body and said inner plate respectively. 120

125

130

2. A hollow furnace door consisting of a body having a rim about the same and inner and outer plates fixed at their edges to said rim, said body dividing the door into front and rear chambers, bolts connecting said inner plate with said body at intervals over its middle portion and air conducting tubes connecting said plate about its edge with said body, said bolts and tubes being alike screwed into said inner plate and secured by nuts to said body.
3. A furnace door having front and rear chambers with a division wall between them, a plurality of transverse tubes threaded into the outer wall of one of said chambers and extending through said division wall into the other chamber, and a jam nut and a fastening nut on each tube engaging the same on opposite sides of said division wall.
4. A double chambered furnace door having a series of tubes open to one of said chambers and passing through the other

chamber, separate outer plates for said chambers respectively and a central part to 25 which said plates are secured having said tubes removably fixed therein.

5. A furnace door with inner and outer chambers having each a separate outer plate and a central member with a rim extending 30 about the outside of said chambers and dividing the same and said plates removably secured to said rim, bolts and tubes 35 removably connecting the outer plate of said inner chamber with said central member and locked thereon and with said plate at their ends, and water supply and exhaust pipes connected with said inner chamber and an air supply connection for said outer chamber.

In testimony whereof I affix my signature in presence of two witnesses.

CARL J. F. JOHNSON.
